(57) **CLAIM**

The ornamental design for a speaker base, as shown and described.

DESCRIPTION

FIG. 1 is a perspective view of a speaker base showing our new design;

FIG. 2 is a front view thereof;

FIG. 3 is a back view thereof;

FIG. 4 is a right view thereof;

FIG. 5 is top plan view thereof; and,

FIG. 6 is a bottom plan view thereof.

Those portions of the figures that are presented in broken lines merely illustrate the environment of the design and are not part of the claimed design.
